CLAIM

The ornamental design for a multi-purpose handle for a portable computing device with thermal venting, as shown and described in FIGS. 1-20.

DESCRIPTION

FIG. 1 is a perspective view of a multi-purpose handle for a portable computing device with thermal venting design according to one embodiment;

FIG. 2 is a back view of the multi-purpose handle for a portable computing device with thermal venting from FIG. 1; FIG. 3 is a front view of the multi-purpose handle for a portable computing device with thermal venting from FIG. 1; FIG. 4 is a side view of the multi-purpose handle for a portable computing device with thermal venting from FIG. 1; FIG. 5 is another side view of the multi-purpose handle for a portable computing device with thermal venting from FIG. 1; FIG. 6 is a top view of the multi-purpose handle for a portable computing device with thermal venting from FIG. 1; and FIG. 7 is a bottom view of the multi-purpose handle for a portable computing device with thermal venting from FIG. 1; and

FIG. 8 is a perspective view of a multi-purpose handle for a portable computing device with thermal venting design according to one embodiment;

FIG. 9 is a back view of the multi-purpose handle for a portable computing device with thermal venting from FIG. 8; FIG. 10 is a front view of the multi-purpose handle for a portable computing device with thermal venting from FIG. 8; FIG. 11 is a side view of the multi-purpose handle for a portable computing device with thermal venting from FIG. 8; FIG. 12 is another side view of the multi-purpose handle for a portable computing device with thermal venting from FIG. 8;

FIG. 13 is a top view of the multi-purpose handle for a portable computing device with thermal venting from FIG. 8; and

FIG. 14 is a bottom view of the multi-purpose handle for a portable computing device with thermal venting from FIG. 8; FIG. 15 is a perspective view of an portable computing device with thermal venting design according to one embodiment; FIG. 16 is a back view of the portable computing device with thermal venting from FIG. 15;

FIG. 17 is a front view of the portable computing device with thermal venting from FIG. 15;

FIG. 18 is a side view of the portable computing device with thermal venting from FIG. 15;

FIG. 19 is another side view of the portable computing device with thermal venting from FIG. 15; and,

FIG. 20 is a top view of the portable computing device with thermal venting from FIG. 15.
